UNITED STATES PATENT OFFICE

2,169,857

PROTECTIVE DEVICE FOR LIQUID IMMERSED ELECTRICAL APPARATUS

Edward D. Treanor, Pittsfield, Mass., assignor to
 General Electric Company, a corporation of
 New York

Application July 30, 1938, Serial No. 222,203

4 Claims. (Cl. 200—81)

My invention relates to protective devices for liquid-immersed electrical apparatus such as 5 transformers and reactors. In accordance with the invention the transformer or other electrical apparatus is immersed in an insulating liquid within a sealed casing which is only partially filled with the liquid so that there is a space 10 filled with air or other gas above the surface of the liquid. Changes in the temperature of the 15 liquid due to different load and ambient temperature conditions cause the liquid to expand and contract with corresponding slow changes in the pressure of the gas above the liquid. Trouble in the apparatus, such as the breakdown of insulation 20 and an arc, however, will cause evolution of additional gas and a rapid increase in pressure within the space of the liquid.

The general object of the invention is to provide an improved protective device for transformers or other electrical apparatus which will respond to a rapid increase in pressure caused by trouble in the apparatus but will not respond to a slow increase in pressure due to changes in 25 normal operating conditions. The protective device may include any form of protective circuit, such as a signal for calling the attention of an attendant to the fact that there is trouble in the apparatus so that he may take proper steps to prevent further trouble, or such as an automatic 30 circuit for disconnecting the apparatus.

The invention will be better understood from the following description taken in connection with the accompanying drawing in which Fig. 1 shows a liquid-immersed transformer provided 35 with a protective device constructed in accordance with the invention, a portion of the transformer casing being broken away to show the transformer and its protective device; Fig. 2 is an enlarged sectional view of the protective device; 40 and Fig. 3 indicates a protective circuit different from that shown in Fig. 1.

Like reference characters indicate similar parts in the different figures of the drawing.

The transformer 10, shown in Fig. 1, is immersed in a body of insulating liquid 11 within a sealed casing 12, the liquid 11 partially filling the casing 12 to leave a space for air or other gas 13 above the surface of the liquid. Changes in the 45 temperature of the liquid 11, due to changes in load and ambient temperature conditions, will cause corresponding changes in the temperature, volume and pressure of the gas 13. Such changes are, however, comparatively slow. Trouble in the 50 transformer, such as a breakdown of insulation 15 accompanied by an arc, however, will cause a

rapid evolution of gas and a consequent rapid increase in pressure within the casing 12. It is 5 obviously desirable that any protective device respond to the rapid increase in pressure resulting from trouble in the apparatus but that no 10 response occur to the slow increase in pressure resulting from normal temperature and pressure changes due to changes in load and ambient temperature conditions.

The protective device 14, as shown most clearly 15 in Fig. 2, includes a cork float 15 in the form of a hollow ring which floats on the surface of the liquid 11 and supports a light metal vessel 16 shaped somewhat like an inverted bottle with its open neck 17 extending down into the liquid 11 20 through the opening 18 in the float 15 and opening below the surface of the liquid. A second cork float 19 floats on the surface of the liquid 11 inside the neck 17 of the vessel 16 and a movable contact 20 is secured to this second float 19 by a 25 stem 21. A guide 22 keeps the float 19 away from the sides of the neck 17 of the vessel 16. A small hole 23 in the top of the vessel 16 permits a slow 30 interchange of gas between the space 24 within the vessel 16 and the space 13 outside of this vessel 16 and above the liquid 11. The pressures in the spaces 24 and 13 are therefore always substantially the same so long as any change in the 35 pressure of the gas in the space 13 above the liquid 11 takes place slowly. If any trouble in the transformer 10 causes the pressure of the gas 13 to increase rapidly, however, the pressure of the gas within the space 24 in the vessel 16 will increase more slowly because gas cannot pass rapidly 40 through the restricted opening 23. This greater 35 pressure of the gas in the space 13 outside the vessel 16 will force the liquid to rise inside the neck 17 of the vessel and this will cause the small float 19 also to rise relatively to the vessel 16 and its supporting float 15 so that the movable contact 45 20 will connect the two contacts 25 which are secured to the float 15 and the vessel 16. These contacts control a protective circuit 26 which, as shown in Fig. 1, includes a battery 27 with a bell 28 to call the attention of an attendant to the 50 trouble in the transformer 10 so that he may disconnect the transformer or take other proper steps to avoid further damage. If desired, the protective circuit 26 may, as shown in Fig. 3, include a battery 27 and an automatic switch 29 for disconnecting the transformer. The device 14 may be retained in any desirable position on the surface of the liquid 11 by a link 30 pivoted at one end to the device 14 and at the other end to the side wall of the casing 12.

The invention provides a simple and reliable protective device for liquid-immersed transformers or other electrical apparatus and a device which will respond in case of electrical trouble in the apparatus, but which cannot give false responses to such slow temperature and pressure changes as occur during normal operation of the apparatus.

The invention has been explained in connection with a liquid-immersed transformer but changes and other applications may obviously be made without departing from the spirit of the invention and the scope of the appended claims.

What I claim as new and desire to secure by Letters Patent of the United States is,—

1. A protective device arranged to float on the surface of insulating liquid, said device including a hollow vessel having an opening at its lower end, a second float within said opening, a contact carried by the second float, and cooperating contacts secured to said vessel, said vessel having a restricted opening in its upper portion.

2. A protective device for liquid-immersed electrical apparatus, said device including a float, a

hollow vessel carried by the float and having an opening at its lower end, a second float within said opening, a contact carried by the second float, and cooperating contacts secured to the first float and vessel, said vessel having a restricted opening in its upper portion.

3. A protective device for liquid-immersed electrical apparatus, said device including a ring-shaped float, a hollow vessel carried by the float and extending through said float with an opening below the surface of the liquid, a second float within said opening, a contact carried by the second float, and cooperating contacts secured to the first float and vessel, said vessel having a restricted opening above the surface of the liquid.

4. A protective device arranged to float on the surface of insulating liquid, said device including a hollow vessel having an opening at its lower end, a second float within said opening, and contacts carried by said floats for controlling a protective circuit, said vessel having a restricted opening in its upper portion.

EDWARD D. TREANOR.
